UNITED STATES PATENT OFFICE.

GEORGE W. STINEBRING, OF SHREVE, OHIO.

FRictional GEARING.

SPECIFICATION forming part of Letters Patent No. 705,714, dated July 29, 1902.

Application filed November 14, 1901. Serial No. 82,215. (No model.)

To all whom it may concern:

Be it known that I, GEORGE W. STINEBRING, a citizen of the United States, residing at Shreve, in the county of Wayne and State of Ohio, have invented certain new and useful Improvements in Frictional Gearing; and I do hereby declare that the following is a full, clear, and exact description of the same, reference being had to the annexed drawings, 10 making a part of this specification, and to the figures of reference marked thereon, in which—

Figure 1 is a perspective view showing a portion of the sawmill frame or bed, and illustrating the carriage feed and return mechanism properly assembled. Fig. 2 is a side view illustrating the position of the friction-wheels, showing the feed-wheels removed. Fig. 3 is a view showing a side elevation of the grooved 15 pulley, also showing the chain connected thereto, and a side view of one of the cams designed to bring the train of friction-wheels into engagement to return the carrier. Fig. 4 is a longitudinal section. Fig. 5 is a detached view of one of the feed friction-wheel supports. Fig. 6 is a top view showing a portion of the mill frame or bed. Fig. 7 is a sectional view of the feed friction-wheel cylinder, also a sectional view of the feed friction- 20 wheel proper. Fig. 8 is a detached view of one of the feed friction-wheel-thimble supports.

The present invention has relation to frictional gearing designed for sawmills and intended to feed the material being sawed to the saw and to run the carriage back after a cut has been made; and it consists in the different parts and combination of parts herein-after described, and particularly pointed out 25 in the claims.

Similar numerals of reference indicate corresponding parts in all the figures of the drawings.

In the accompanying drawings, 1 represents 30 the saw-shaft, which is of ordinary construction and is journaled to the sawmill frame or bed in the usual manner and is provided with the power-pulley 2.

Upon the saw-shaft 1 is located the friction-pulley 3, which friction-pulley is located substantially as shown in the drawings and is securely attached to the saw-shaft 1 in the

usual manner. Against the face or periphery of the friction-pulley 3 is located the intermediate feed-wheel 4, said wheel being at 55 all times held in close contact with the periphery of the friction-pulley 3.

Adjacent to the feed-wheel 4 is located the wheel 5, which wheel is provided with the beveled face 6, and for the purpose of moving the wheel 5 out of engagement with the feed-wheel 4 during the time the carriage is fed forward the feed-shaft 7 is journaled at one end to the swinging boxing or bearing 8, which boxing or bearing is provided with upward-extending arm 9, which arm is pivoted to one of the sills of the base or sawmill frame. 65

For the purpose of imparting rotary motion to the intermediate wheel 4 and the wheel 5 said wheels are provided with flat peripheries; 70 and the flat-faced peripheries of the intermediate wheel 4 are in contact with the flat face or periphery of the wheel 3.

To the cross-bar 10 is securely attached in any convenient and well-known manner the 75 bracket-bearing 11, which bracket-bearing is formed of a sufficient length to properly hold the rotatable head 12, which rotatable head is eccentrically mounted upon the shaft 13 and upon which shaft is securely mounted 80 the beveled friction-wheel 14, which beveled friction-wheel imparts rotary motion to the wheel 5 as it comes in contact with the beveled face 6, formed upon the side of said wheel. 85

For the purpose of imparting rotary motion to the shaft 13 and the beveled friction-wheel 14 the friction-wheel 15 is provided, which friction-wheel is slidably mounted upon the shaft 13 and is so located that it will come in 90 contact with the side face of the intermediate wheel 4 when it is desired to move the carriage forward to feed vertically to the saw.

It will be understood that when the wheel 3, which wheel is mounted upon the saw-shaft 1, is rotated it will impart rotary movement to the wheel 4, which in turn imparts rotary movement to the wheel 15 when said wheel is brought in contact with the face of the wheel 4. The rotatable head 12 is provided with the toothed segment 16, which toothed segment meshes with the toothed segment 17, said segment 17 being securely attached to the shaft 18, which shaft extends 95 100

rearward, and to its rear end is pivotally attached the operating-lever 19, said operating-lever being extended upward a sufficient distance to give the desired amount of leverage to operate the different parts, as hereinafter described.

The operating-lever 19 is extended downward below the shaft 18, and to its bottom or lower end is pivotally attached the rod 20, to which rod is pivotally attached the connecting link or bar 21, which connecting link or bar is connected to the arm 22, which arm is preferably formed integral with the band 23, said band 23 being mounted upon the hub 24 of the wheel 15, and for the purpose of holding the band 23 in proper position upon the hub 24 the plate 25 is securely connected to the hub 23 by means of a set-screw 26 or its equivalent.

20 It will be understood that when the operating-lever 19 is moved so as to impart a reciprocating motion to the rod 20 the friction-wheel 15 will be moved to or from the center of the intermediate friction-wheel 4, thereby changing the speed of the friction-wheel 15, it being understood that when the friction-wheel is forced toward the periphery of the friction-wheel 4 a rapid motion will be imparted and a slower motion imparted when it is brought toward the center of the intermediate friction-wheel 4, by which arrangement a rapid or slow motion is imparted to the feed-shaft 7 by means of the wheel 5 and the bevelled gear-wheel 14.

30 35 It will be understood that the friction-wheel 15 should be slidably mounted upon the shaft 13 and that said friction-wheel should be so connected that it will impart a rotary movement to the shaft 13.

40 45 50 For the purpose of limiting the outward movement of the friction-wheel 15 the shaft 13 should be provided with a stop-pin or its equivalent, such as 27. The intermediate friction-wheel 4 is mounted upon the shaft 28, which shaft is held in the bearing 29, said bearing being held in proper alignment by means of the yoke 30, which yoke is adjustable back and forth in the plate 31, which plate is connected to one of the sills of the sawmill-frame or its equivalent.

55 The yoke 30 extends rearward and is provided with a slot 32, through which slot the clamping-bolts 33 are passed, said bolts also being passed through the sill of the sawmill-frame.

60 The object and purpose of providing the adjustable yoke 30 is to adjust the shaft 28 so as to bring the intermediate friction-wheel 4 into true alignment between the wheels 3 and 5.

65 For the purpose of holding the outer end of the bearing 29 the yoke 34 is provided, which yoke is attached to a sill of the sawmill-frame. The bearing 29 is provided with the screw-threaded cap 35, through which screw-threaded cap extends the screw-threaded bolt 36, said bolt being so arranged that it will come

against the end of the shaft 28, and thereby prevent any end movement of said shaft, this arrangement being desirable to bring to proper adjustment the intermediate friction-wheel 4 with reference to the sliding friction-wheel 15.

The shaft 18 is held against end movement during the time the lever 19 is moved to impart a reciprocating motion to the rod 20 by means of suitable collars 37, which collars are located upon opposite sides of the cross-bar 38 of the sawmill-frame proper.

To the bracket-bearing 11 is attached or formed integral therewith the arm 39, which arm forms a support and bearing for the shaft 18.

For the purpose of forcing the friction-wheel 5 against the intermediate friction-wheel 4 when it is desired to bring the carriage back after a cut has been made the swinging bearing 8 is provided with the shaft 40, which shaft is journaled to the free end of the swinging bearing 8 and is provided with the cam-faced disk 41, which cam-faced disk rests against the cam-face disk 42.

The cam-face disk 41 is provided with the arm 43, to which arm is attached the chain 44, said chain being connected to the grooved pulley 45, which grooved pulley or its equivalent is fixed to the shaft 18. By imparting an auxiliary movement to the shaft 18 by means of the lever 19 the grooved pulley 45 will be turned, and when turned in one direction the faces of the cam-disks 41 and 42 will ride upon each other, thereby imparting a longitudinal movement to the rod 40 and crowd the swinging bearing 8 in the direction to force the wheel 5 against the intermediate wheel 4, this movement being brought about by a lateral motion being imparted to the operating-lever 19. When a lateral movement is imparted to the lever 19 in one direction, the direction being the same that forces the wheel 5 against the intermediate wheel 4, the friction-wheel 15 and the bevelled friction-wheel 14 will be moved away from the bevelled face 6 of the wheel 5 and the face of the intermediate friction-wheel 4, this movement being brought about by means of the toothed segments 16 and 17, which segments act to impart a rocking movement to the rotatable head 12, and by rotating said head the shaft 13 is moved to or from the wheels 4 and 5, this being accomplished by journaling said shaft eccentrically to the rotatable head 12.

After the carriage has been run back for a new cut the operating-lever 19 is so manipulated that the friction-wheels 15 and 14 will be brought against the contact-faces of said wheels, and at the same time the wheel 5 will be released from contact with the intermediate friction-wheel 4.

It will be understood that the cam-disk 42 should remain at rest at all times, so that as the cam-disk 41 is rotated it will move the rod 40 endwise, and for the purpose of accomplishing this object the disk 42 should be

loosely mounted upon the rod 40 and held against end movement in any well-known manner.

For the purpose of at all times holding the 5 inclined faces of the cam-disks 41 and 42 together a spring, such as 47, is provided, said spring being interposed between the disk 41 and a suitable flange 48, which flange is secured to the proper sill of the sawmill frame 10 or bed.

For the purpose of assisting in holding the bearing 29 in true vertical position the plate 49 is provided, which plate is provided with the elongated slot 50, said slot being so formed 15 that it will not allow any vertical movement of the bearing 29, but will permit a limited horizontal movement of said bearing 29.

The object and purpose of providing the screw-threaded bolt 36 and passing the same 20 through the cap 35 is to provide suitable adjustment from time to time between the faces of the intermediate friction-wheel 5 and the friction-wheel 15.

It will be understood that rotating the 25 screw-threaded bolt 36 will change the position of the axle 28, which in turn moves the intermediate friction-wheel 4 laterally. This adjustment is of course limited and is only intended to compensate for the wearing away 30 of the surfaces of the intermediate wheel 4 and the friction-wheel 15.

It will be understood that the shaft 7 is to be provided with the ordinary pinion, which meshes with the common rack-bar employed 35 to impart movement to the driving-carriage; but as these parts are old and common they are not illustrated, as they form no particular part of the present invention except that they are necessary elements in the complete working 40 of a sawmill.

Having fully described my invention, what I claim as new, and desire to secure by Letters Patent, is—

1. The combination of a train of friction-wheels, an eccentrically-journalized shaft, a friction-wheel slidably mounted upon the shaft, a rotatable head, carrying the shaft provided with the sliding friction-wheel, and provided with a toothed segment, a toothed 45 segment to mesh with the segment of the head, said segment fixed to a shaft, the shaft provided with an operating-lever, the operating-lever extended below its pivotal point, and a rod connected to the lower end of the 50 operating-lever, a link connected to the rod and to an arm, said arm fixed to the band and said band located around the hub of the sliding friction-wheel, a beveled friction-wheel mounted upon the eccentrically-journalized shaft, and one of the train of friction- 55

wheels provided with a beveled side face, substantially as and for the purpose specified.

2. The combination of a driving-shaft, a train of friction-wheels, one of the train mounted upon the driving-shaft, a shaft for 65 the intermediate wheel of the train, and the other wheel of the train provided with a beveled side, a beveled friction-wheel located adjacent to the beveled side of one of the train of wheels, a rotatable head, and a shaft, eccentrically journaled in the head, a sliding friction-wheel mounted upon the eccentrically-journalized shaft and located opposite the intermediate wheel, means for sliding the 70 sliding friction-wheel and means for rotating the head carrying the eccentrically-journalized shaft, substantially as and for the purpose set forth.

3. The combination of a driving-shaft, a friction-wheel mounted thereon, an intermediate friction-wheel located in contact with the friction-wheel, upon the driving-shaft, a feed-wheel and shaft, the shaft of the feed-wheel journaled in a swinging bearing, and the feed-wheel provided with a beveled face 80 located upon its side, a beveled friction-wheel located adjacent to the beveled side of the feed-wheel, an eccentrically-journalized shaft, a sliding friction-wheel located upon the eccentrically-journalized shaft, a rotatable head 85 carrying the eccentrically-journalized shaft, means for rotating said head, and means for sliding the friction-wheel back and forth upon its shaft, substantially as and for the purpose specified.

4. The combination of a driving-shaft, a train of friction-wheels, one of said wheels mounted upon the driving-shaft, a swinging shaft and an arm, a feed-wheel constituting one of the train, mounted upon the swinging 90 shaft, a shaft provided with an operating-lever, a grooved pulley fixed to the shaft having the operating-lever, a chain secured to the grooved pulley and to an arm, the arm fixed to the shaft 95 40, and the said shaft connected at one end, to the bearing of the swinging shaft, a cam fixed to the shaft provided with the grooved pulley, and a fixed cam located adjacent to the cam upon the shaft 40, a sliding friction-wheel located adjacent to the face of the intermediate 100 friction-wheel and an eccentrically-journalized shaft, substantially as and for the purpose set forth.

In testimony that I claim the above I have hereunto subscribed my name in the presence 115 of two witnesses.

GEORGE W. STINEBRING.
